E. A. MELLINGER,
SEMI-AUTOMATIC TELEPHONE SYSTEM.
APPLICATION FILED MAY 9, 1913.

1,186,817.

Patented June 13, 1916.

UNITED STATES PATENT OFFICE.

EDWARD A. MELLINGER, OF CHICAGO, ILLINOIS, ASSIGNOR TO AUTOMATIC ELECTRIC COMPANY, OF CHICAGO, ILLINOIS, A CORPORATION OF ILLINOIS.

SEMI-AUTOMATIC TELEPHONE SYSTEM.

1,186,817.

Specification of Letters Patent. Patented June 13, 1916.

Application filed May 9, 1913. Serial No. 766,559.

To all whom it may concern:

Be it known that I, EDWARD A. MELLINGER, a citizen of the United States of America, and resident of Chicago, Cook county, Illinois, have invented a certain new and useful Improvement in Semi-Automatic Telephone Systems, of which the following is a specification.

My invention relates to improvements in semi-automatic telephone systems, and it relates more particularly to means for automatically connecting an operator's calling device with an idle trunk.

My invention is adapted for use in a system in which calls are received on a manual board, from which board the call is to be extended through automatic switches to the called line. In such a system, according to my invention, each of the operators upon the manual board has a calling device for transmitting impulses to control these automatic switches, and each operator has access to a plurality of trunk lines leading to these automatic switches.

An object of my invention is to provide means associated with these calling devices whereby, when an operator operates her calling device in accordance with the called number, this calling device is automatically connected with an idle trunk line.

A further object is the provision of a signal associated with each trunk line to indicate with which trunk the calling device has been connected.

A further object is the provision of means for automatically disconnecting the calling device from the selected trunk when the operator plugs into the jack of the trunk in order to extend the talking connection over this trunk.

These and other objects of my invention will be more clearly understood by reference to the accompanying drawings, in which I have represented diagrammatically a manual calling line and an operator's cord circuit connected with a trunk line. It is to be understood that this trunk line represents one of a plurality of trunks which extend to an automatic exchange, a connection to a called subscriber's line being completed

through the ordinary selectors and connectors of such exchange. These switches being of a well-known type, it is not thought necessary to illustrate the same in the drawings.

The manual substation A may be of any suitable or approved type and, as shown herein, comprises the receiver 2, transmitter 3, switch hook 4, ringer 5 and condenser 6.

At the central office the line of the substation A is provided with an answering jack J', one or more multiple jacks J, a double-wound line relay 13, cut-off relay 14 and line lamp 15.

The operator's cord C is adapted for use for either connecting two manual lines or for connecting a manual line with the automatic exchange. This cord comprises the usual answering and calling plugs P¹ and P² connected together through the condensers 28 and 29. The supervisory circuits of the cord are controlled through the medium of the relays 30, 31, 32 and 33. The relays 30 and 33 are double-wound polarized relays of any desired construction. As shown herein, the winding of the relay is mounted between the two limbs of a U-shaped permanent magnet. The two windings of the relays 30 and 33 are normally bridged in series across the cord circuit through the contacts of the relays 31 and 32. When either of the relays 31 or 32 is energized, one winding of the corresponding relay 30 or 33 is connected to ground and the other winding of said relay is connected to the non-grounded terminal of the battery. The cord circuit is provided with the usual ringing keys K¹ and K². An answering key K is provided for the purpose of connecting the operator's talking set S with the cord. The trunk circuit leading to the automatic exchange is provided with a multiple jack J² upon each operator's position in the manual board. The sleeve conductors of the jack J² are connected to the battery lead 35 through the winding of a relay 34. Each trunk is also provided with a visual busy signal 36 on each operator's position. Each trunk is also provided with a slow-acting

relay 37 which is rendered slow to deenergize by the provision of a ring of copper around one end of the core.

- In order to complete calls through an automatic exchange, each operator is provided with an automatic calling device, represented herein by an impulse wheel 38 and impulse springs 39, 40, 41 and 42. The impulse wheel 38 may be conveniently controlled by the operator through the medium of a dial provided with finger holes in a well-known manner. The impulse wheel is preferably arranged so that as the calling device is operated, preparatory to calling any digit, the impulse tooth 39 momentarily forces the spring 40 into contact with the spring 39, after which a certain number of the teeth 43, corresponding to the digit to be called, are rotated past the end of the spring 41 without separating said spring from the spring 42. As the impulse wheel returns to normal position after being thus operated, the teeth 43, after they pass the end of the spring 41, separate said spring from the spring 42 a number of times corresponding to the digit to be called. The spring 39 should be arranged so as not to operate the spring 40 during the return movement of the impulse wheel.
- For connecting the operator's calling device with the trunk lines there is allotted to each operator's position an automatic switching mechanism D. As shown herein, this switching mechanism is similar in general respects to the subscriber's individual or line switch disclosed in British patent to R. W. James No. 26,301 of 1903. This switch comprises a plunger 45 carried upon the end of a so-called plunger arm 43. The plunger 45 is normally held in its retracted position, as shown in the drawing, by the engagement of a catch on the armature of the magnet 47 with the rear end of the plunger arm 46. When the magnet 47 is energized, the plunger arm is released and the spring 48 draws said plunger downward, causing the lower end thereof to force the springs 49, 50 and 51 into engagement with the springs 52, 53 and 54, respectively. The springs 51 and 53 are connected with the impulse springs 42 and 41 of the calling device, while the springs 50 and 51 are connected with the trunk conductors 107 and 108. Although only one set of springs 49-54 is shown, the switch D is provided with a plurality of such sets, one for each trunk line leading to the automatic exchange. These sets of springs are arranged on the arc of a circle opposite the end of the plunger 46, and are in reality rotated through an angle of ninety degrees from the position shown, so that as the plunger oscillates back and forth about its pivot 56 its lower end will move back and forth across its sets of contact springs. The

means for moving the plunger back and forth comprises the master switch E. The rear end of the plunger 45 normally engages a V-shaped slot in a so-called plunger shaft 57. This shaft 57 is controlled through the medium of the motor magnet 58 of the master switch, ratchet wheel 59 and the arm 60. In the ratchet wheel 59 there are a number of pins 61 which cooperate with the arm 60 in such a manner as to cause the plunger shaft 57 to oscillate about the point 57 as an axis to move the end of the plunger 45 from one set of bank springs to another each time the magnet 58 is energized. When the plungers reach a position opposite the last trunk terminal and the magnet 58 is again energized, the pin 61, which is then in engagement with the arm 60, passes beyond the end thereof, whereupon the spring 62 draws the arm 60 down until it strikes the next pin 61, whereby the plungers are returned to a position opposite the first trunk. Associated with the master switch there is a bank of contacts comprising the common segment 63 and an individual contact *a* for each of the trunk lines. The wiper 64 is adapted to maintain the common segment 63 in electrical connection with the individual contact of the trunk line before which the plunger of the switch D is resting. One master switch E may control the switches D of all the operators who have access to the same group of trunk lines—that is, all of said switches D may be arranged side by side and their plungers caused to engage the same plunger shaft 57. Each pair of trunk conductors 107 and 108 is connected with the springs 50 and 51 of corresponding sets in the banks of all the switches D, while the springs 41 and 42 of each calling device are connected with the springs 53 and 54 of all the sets in the banks of its own switch.

Having given a general description of the apparatus, it will now be explained in detail how the calling manual subscriber obtains connection with a trunk line leading to an automatic exchange. The removal of the receiver at the calling substation closes a bridge across the line through the transmitter 3, thereby energizing the line relay 13 at the central office in the usual manner. The relay 13, upon energizing, closes the circuit of the line lamp 15. Upon noting the signal displayed by the lamp, the operator inserts the plug *P* of the cord *C* into the answering jack *J* and operates the answering key *K* to connect the talking set *S* with the cord and inquires the number of the line desired. Upon learning that a connection with a line in the automatic exchange is desired, the operator restores the key *K* and then begins to operate the calling device in accordance with the number called for. It will be understood that the plunger

83 *Wetzel, 1860* is the name of a genus of beetles
84 and probably the author of the name is not known.

plurality of trunk lines terminating in jacks with which said cord circuit is adapted to be connected, an operator's set associated with said cord, and a calling center associated with said set and controllably disconnected from said trunk, said calling device including a rotary dial, means operated upon the forward rotation of said dial for automatically connecting the said calling device with an idle one of said trunks, and means operated upon the backward rotation of said dial for transmitting a series of impulses over the selected trunk.

2. In a telephone system, a cord circuit, a plurality of trunk lines terminating in jacks with which said cord circuit is adapted to be connected, an operator's set associated with said cord, a calling device associated with said set and normally disconnected from said trunks, said calling device including a rotary dial, means operated upon the forward rotation of said dial for automatically connecting the said calling device with an idle one of said trunks, means operated upon the backward rotation of said dial for transmitting a series of impulses over the selected trunk, and a signal associated with each trunk for indicating to the operator the trunk with which said calling device has been connected.

3. In a telephone system, a cord circuit, a plurality of trunk lines terminating in jacks with which said cord circuit is adapted to be connected, an operator's set associated with said cord, a calling device associated with said set and normally disconnected from said 100 trunks, said calling device including a rotary dial means operated upon the forward rotation of said dial for automatically connecting the said calling device with an idle one of said trunks, means operated upon the backward rotation of said dial for transmitting a series of impulses over the selected 105 trunk, and means for again disconnecting said calling device from said trunks when 110 the operator connects the cord circuit with the jack of the selected trunk.

1,310 a telephone system, a cord circuit, a plurality of trunk lines terminating in jacks with which said cord circuit is adapted to be connected, an operator's set interconnected with said circuit, a calling device associated with said set and internally interconnected therewith, said calling device including a resistor diode means, positioned upon the 1320 terminal conduct of said circuit, for automatically connecting the said calling device with an idle one of said trunk lines in accordance with the telephone system, and a carrier line for transmitting signals between said calling line and selected telephone sets, interconnected with all telephone sets, and for connecting for the single telephone set which has been connected to the calling device, a telephone line, said telephone line being connected to the telephone set and to the telephone system.

trunks when the operator connects the cord circuit with the jack of the selected trunk.

5. In a telephone system, a cord circuit, a plurality of trunk lines terminating in jacks with which said cord is adapted to be connected, an operator's set associated with said cord, a calling device associated with said operator's set and normally disconnected from said trunk lines, a line switch, means controlled by the initial operation of said calling device for tripping said line switch to connect said calling device with one of said trunks, and a master switch for controlling said line switch, whereby for controlling said line switch, whereby said line switch makes connection with an idle trunk.

6. In a telephone system, a cord circuit, a plurality of trunk lines terminating in jacks with which said cord is adapted to be connected, an operator's set associated with said cord, a calling device associated with said operator's set and normally disconnected from said trunk lines, a line switch, means controlled by the initial operation of said calling device for tripping said line switch to connect said calling device with one of said trunks, a master switch for controlling said line switch, whereby said line switch makes connection with an idle trunk, and a signal associated with each trunk for indicating to the operator the trunk with which said calling device has been connected.

7. In a telephone system, a cord circuit, a plurality of trunk lines terminating in jacks with which said cord is adapted to be connected, an operator's set associated with said cord, a calling device associated with said operator's set and normally disconnected from said trunk lines, a line switch, means controlled by the initial operation of said calling device for tripping said line switch to connect said calling device with one of said trunks, a master switch for controlling said line switch, whereby said line switch makes connection with an idle trunk, and means for again disconnecting said calling device from said trunks when the operator connects the cord circuit with the jack of the selected trunk.

8. In a telephone system, a cord circuit, a plurality of trunk lines terminating in jacks with which said cord is adapted to be connected, an operator's set associated with said cord, a calling device associated with said operator's set and normally disconnected from said trunk lines, a line switch, means controlled by the initial operation of said calling device for tripping said line switch to connect said calling device with one of said trunks a master switch for controlling said line switch, whereby said line switch makes connection with an idle trunk, a signal associated with each trunk for indicating to the operator the trunk with which said calling device has been connected, and means

for again disconnecting said calling device from said trunks when the operator connects the cord circuit with the jack of the selected trunk.

9. In a telephone system, a cord circuit, a plurality of trunk lines terminating in jacks with which said cord is adapted to be connected, an operator's set associated with said cord, a calling device associated with said operator's set and normally disconnected from said trunks, said calling device comprising a rotary dial adapted to be rotated forward and back, a line switch, means for tripping said line switch upon the forward rotation of said dial to connect with one of said trunks, a master switch for controlling said line switch, whereby said line switch makes connection with an idle trunk, and means controlled by the backward rotation of said dial for transmitting a series of impulses over the selected trunk.

10. In a telephone system, a cord circuit, a plurality of trunk lines terminating in jacks with which said cord is adapted to be connected, an operator's set associated with said cord, a calling device associated with said operator's set and normally disconnected from said trunks, said calling device comprising a rotary dial adapted to be rotated forward and back, a line switch, means for tripping said line switch upon the forward rotation of said dial to connect with one of said trunks, a master switch for controlling said line switch, whereby said line switch makes connection with an idle trunk, means controlled by the backward rotation of said dial for transmitting a series of impulses over the selected trunk, and a signal associated with each trunk for indicating to the operator the trunk with which said calling device has been connected.

11. In a telephone system, a cord circuit, a plurality of trunk lines terminating in jacks with which said cord is adapted to be connected, an operator's set associated with said cord, a calling device associated with said operator's set and normally disconnected from said trunks, said calling device comprising a rotary dial adapted to be rotated forward and back, a line switch, means for tripping said line switch upon the forward rotation of said dial to connect with one of said trunks, a master switch for controlling said line switch, whereby said line switch makes connection with an idle trunk, means controlled by the backward rotation of said dial for transmitting a series of impulses over the selected trunk, and means for again disconnecting said calling device from said trunks when the operator connects the cord circuit with the jack of the selected trunk.

12. In a telephone system, a cord circuit, a plurality of trunk lines terminating in jacks with which said cord is adapted to be connected, an operator's set associated with

said cord, a calling device associated with said operator's set and normally disconnected from said trunks, said calling device comprising a rotary dial adapted to be rotated forward and back, a line switch, means for tripping said line switch upon the forward rotation of said dial to connect with one of said trunks, a master switch for controlling said line switch, whereby said line switch makes connection with an idle trunk, means controlled by the backward rotation of said dial for transmitting a series of impulses over the selected trunk, a signal associated with said trunk for indicating to the operator the trunk with which said calling device has been connected, and means for thereby disconnecting said calling device from said trunk when the operator connects the cord circuit with the jack of the selected trunk.

11. In a telephone system, a cord circuit, a plurality of trunk lines terminating in jacks with which said cord is adapted to be connected, an operator's set associated with said cord, a calling device associated with said operator's set and normally disconnected from said trunk lines, a line switch, means controlled by the initial operation of said calling device for tripping said line switch with one of said trunks, a master switch for controlling said line switch, whereby said line switch makes connection with an idle trunk, a request magnet for said line switch, and means for momentarily energizing and then de-energizing said magnet when said cord circuit is connected with the selected trunk, thereby disconnecting said calling device from said trunk lines.

12. In a telephone system, a cord circuit, a plurality of trunk lines terminating in jacks with which said cord is adapted to be connected, an operator's set associated with said cord, a calling device associated with said operator's set and normally disconnected from said trunks, said calling device comprising a rotary dial adapted to be rotated forward and back, a line switch, means for tripping said line switch upon the forward rotation of said dial to connect with one of said trunks, a master switch for controlling said line switch, whereby said line switch makes connection with an idle trunk, means controlled by the backward rotation of said dial for transmitting a series of impulses over the selected trunk, a release magnet for said line switch, and means for momentarily energizing and then de-energizing said magnet when said cord circuit is connected with the selected trunk, to thereby disconnect said calling device from said trunk lines.

13. In a telephone system, a plurality of jacks and an operator's equipment com-

prising a cord circuit, a plurality of trunk lines, a calling device, a master switch, a line switch, and means for automatically connecting the calling device with an idle one of said trunks.

14. In a telephone system, a plurality of jacks and an operator's equipment comprising a cord circuit, a plurality of trunk lines, a calling device, a master switch, a line switch, and means for automatically connecting the calling device with an idle one of said trunks, a signal associated with each of said trunks for indicating to the operator the trunk with which the calling device has been connected, and means for disconnecting the calling device from said trunk when the operator connects the cord circuit with the jack of the selected trunk.

15. In a telephone system, a plurality of jacks and an operator's equipment comprising a cord circuit, a plurality of trunk lines, a calling device, a master switch, a line switch, and means for automatically connecting the calling device with an idle one of said trunks, means for momentarily energizing and then de-energizing said magnet when said cord circuit is connected with the selected trunk, and means for disconnecting the calling device from said trunk when the operator connects the cord circuit with the jack of the selected trunk.

16. In a telephone system, a plurality of jacks and an operator's equipment comprising a cord circuit, a plurality of trunk lines, a calling device, a master switch, a line switch, and means for automatically connecting the calling device with an idle one of said trunks, and means for momentarily energizing and then de-energizing said magnet when said cord circuit is connected with the selected trunk, thereby disconnecting the calling device from said trunk.

17. In a telephone system, a trunk 106 and a line 108, a master switch for connecting said line to one of a plurality of jacks, a switch for operating said master switch, a master switch for connecting the line to another of the jacks, a switch for operating said master switch, a calling device, a line switch, and means for automatically connecting the calling device with an idle one of the jacks, and means for disconnecting the calling device from said trunk.

18. In a telephone system, a line, a trunk and an automatic switch for connecting said line with another line, a calling device for operating said automatic switch to connect 120 with said other line, a non-numerical switch for connecting said calling device with said trunk to operate said automatic switch, said non-numerical switch controlled by said calling device, and a master switch for connecting said line with another line.

19. In a telephone system, a line, a trunk and an automatic switch for connecting said

line with another line, a calling device for
operating said automatic switch to connect
with said other line, another automatic
switch for connecting said calling device
5 with said trunk to operate said automatic
switch, said other switch controlled by said
calling device, means for thereafter connect-
ing said line with said trunk, and means con-

trolled by said last mentioned means for re-
leasing said other switch.
